(57) **CLAIM**

We claim the ornamental design for a removable cover for an aerosol generator, as shown and described.

DESCRIPTION

FIG. 1 is a top front perspective view of a removable cover for an aerosol generator showing the claimed design;

FIG. 2 is a top rear perspective view thereof;

FIG. 3 is a bottom rear perspective view thereof;

FIG. 4 is a top view thereof;

FIG. 5 is a bottom view thereof;

FIG. 6 is a front view thereof;

FIG. 7 is a rear view thereof;

FIG. 8 is a left view thereof; and,

FIG. 9 is a right view thereof.

The broken lines in the drawings illustrate portions of the removable cover for an aerosol generator that form no part of the claimed design.

The dot-dash broken lines in the drawings illustrate boundaries of the removable cover for an aerosol generator that form no part of the claimed design.
